UNITED STATES PATENT OFFICE.

JAMES C. HENRY, OF EAST ST. LOUIS, ILLINOIS.

CARBURETER.

1,364,110.

Specification of Letters Patent.

Patented Jan. 4, 1921.

Application filed July 7, 1915. Serial No. 38,422.

To all whom it may concern:

Be it known that I, JAMES C. HENRY, a citizen of the United States, and a resident of East St. Louis, county of St. Clair, State of Illinois, have invented certain new and useful Improvements in Carbureters, of which the following is a specification.

The main object of my invention is to provide an improved construction of carbureter in which the oil is more completely vaporized and mixed and intermingled with the air than heretofore has been possible so that an increased efficiency is effected.

A further object of my invention is to provide a carbureter having an atomizing chamber or passage-way which is tapering in one direction from the point at which the mixture of fuel and air are delivered thereto and which widens and flares outwardly in a direction at right angles to the tapering direction.

Other objects and advantages of my invention will be pointed out in the detailed description thereof which follows or will be apparent from such description.

In order that my invention may be more readily comprehended and understood, reference may be had to the accompanying drawings in which I have illustrated certain forms of construction embodying the same but it should be understood that changes in the details of construction may be made within the scope of the claims without departing therefrom.

In the drawings—

Fig. 1 is a vertical sectional view of a carbureter embodying my invention;

Fig. 2 is an enlarged view of a portion of the mechanism thereof, partly in side elevation and partly in section;

Fig. 3 is an enlarged bottom plan view of certain parts of the mechanism;

Fig. 4 is a top plan view of the carbureter;

Fig. 5 is a fragmentary elevational view showing a portion of the controlling mechanism of the carbureter;

Fig. 6 is a view showing a circular valve in flattened out or projected position;

Fig. 7 is a detail view partly in section and partly in top plan showing part of an auxiliary fuel feeding means for the carbureter;

Fig. 8 is a vertical longitudinal sectional view of a modified construction of carbureter embodying my invention;

Fig. 9 is a horizontal sectional view taken on the line 9—9 of Fig. 8 with the air control valve in different position from that in which it is shown in said Fig. 8; 60

Fig. 10 is a horizontal sectional view taken on the line 10—10 of Fig. 8; and

Fig. 11 is a view showing a circular valve in flattened or projected position.

In the drawings, 1 designates the lower 65 section of the hollow body portion of the carbureter and 2 the upper section thereof, the two sections being secured together in any suitable known manner, as by bolts 2^a. Air is permitted to enter the interior of the 70 carbureter through an inlet opening 3 provided in the upper section 2.

In the form of construction shown in Figs. 1 to 7 inclusive 4 designates a valve supported upon a spring pressed rod 4^a, 75 said valve 4 being provided with holes 4^b therein for the passage of air, said holes being controlled by an adjustable rotatable valve 4^c having holes 4^d therein which are adapted to register with the holes 4^b. The 80 upper section 2 is also provided with an outlet passage 5 for the passage of the fuel mixture from the carbureter said passage being controlled by means of the pivoted butterfly valve 6 which is shown partially 85 open in Fig. 1. By adjusting the nut upon the rod 4^a the tension of the spring 4^c is varied so that the force required to depress the valve 4 to open it is varied.

The bottom wall of the section 1 of the 90 carbureter body is inclined as shown in Fig. 1 of the drawings and at its interior central portion is provided with a projection 6^a having a valve seat 7, said valve seat being formed at the upper extremity of the passage 8 which extends through the projection 6^a, the lower wall of section 1 of the carbureter and a portion 9 depending from said lower wall. The passage 8 terminates at its lower extremity in a cock 10 which is 100 employed to drain the carbureter if necessary.

Extending centrally through the body of the carbureter is a valve member 11 of the needle type which valve has screw-threaded 105 engagement at its upper end with the section 2 as is indicated at 12. The upper extremity of the said valve is knurled as at 13 to facilitate the turning thereof so as to adjust the lower end thereof toward and from the valve seat 7. The lower end of the said valve member 11 is tapered as shown at 14

whereby it coöperates satisfactorily with the valve seat 7. By regulating the valve 11 so as to adjust the relation of its lower tapered end with respect to the valve seat 7 the supply of fuel to the carbureter is regulated and controlled.

The passage-way 8 is connected with the float chamber 16 by means of a passage-way 15. The float chamber 16 is of known type 10 and is supplied with liquid hydrocarbon from the fuel tank (not shown) through the passage-way 17 which passage-way is controlled by means of a valve 19 which in turn is controlled by means of a float 18 and 15 the pivoted radially situated levers 20^a.

It will be understood that when the float chamber 16 is empty or substantially so, the float 18 rests upon the outer ends of the lever 20^a. The weight of the float combined with the weight of the outer end portion of the levers 20^a is sufficient to cause the inner ends of said levers to lift the said valve 19 out of engagement with its seat at the inner end of the passage-way 17. When 25 this occurs the fuel flows through the said passage-way 17 into the chamber 16 and causes upward movement of the float 18. Such upward movement removes the weight of the said float from the levers 20^a. When 30 this occurs the valve 19 actuated by gravity assisted by the spring 19^a returns to closed position as illustrated in Fig. 1 of the drawings.

Supported between the upper section 2 35 and the lower section 1 of the body portion of the carbureter is a centrally arranged rotatable spindle 20 having an axial opening or bore therethrough, through which the valve member 11 extends.

40 21 designates a circular member, shown in Figs. 2 and 3, which member is carried upon and fixedly secured to the upwardly extending projection 6^a. The lower end of the spindle 20 rests upon the member 21 and 45 upon the horizontal wall 23 of an annular member, designated as a whole by the reference number 22, which is secured to the member 21, said annular member being circular in top plan and having a wall 24 depending vertically from the horizontal wall 23, said wall 24 depending to a point in proximity to a plane coincident with the lower end of the member 21.

The vertical annular wall 24 is provided 55 with a plurality of perforations 25 arranged in rows situated respectively at its upper and lower edge portions, as indicated in Figs. 1 and 2 of the drawings. The purpose of these perforations is to permit the passage of air into the mixing chamber to be hereinafter described. The vertical wall 24 is also provided with a third row or series 60 of perforations 30 which are situated intermediate the upper and lower rows of perforations 25.

The horizontal wall 23 of the member 22 is also provided with a plurality of air openings 26 as shown in Fig. 3.

The member 22, as illustrated, may be removed and another member substituted 70 therefor, changing the air and fuel openings therein as desired.

The member 21 is provided with a central passage 27 of greater diameter than the valve member 11 from which extends a plurality of passage-ways 28, as shown in Fig. 2 of the drawings.

Nozzles 29 are secured in these passage-ways 28, the outer ends of which nozzles are situated in alinement with and in proximity 80 to the respective perforations 30. The liquid fuel is discharged from the nozzles 29 into the perforations 30 and by reason of its power of adhesion a greater or less portion thereof adheres to the edges of said perforations.

By reason of the simultaneous forcing of air through the perforations 30 it will be understood that a spray is formed consisting of a mixture of air and the hydrocarbon. 90 In other words, the fuel is atomized.

31 designates an annular, removable and interchangeable valve which is secured to the rotatable spindle 20 a short distance from its lower end. The lower edge of the 95 said annular valve is situated in a plane substantially coincident with the lower edge of the vertical wall 24 of the annular member 22. The annular valve 31 is provided with a plurality of circular openings 32 and 100 a plurality of oblong openings 33 said openings being of different lengths.

The respective groups of openings are arranged in rows peripherally of the said valve. The series of openings 32 are separated from the openings 33 by an intermediate solid or unbroken portion 35. The purpose of making the openings 33 of different lengths is to provide means whereby the openings 25 and 30 in the vertical wall 110 24 of the annular member 22 may be successively opened or closed.

The valve 31 is operated synchronously with and automatically as the butterfly valve 6 is operated by means which will be 115 hereinafter referred to and described.

Located within the section 1 of the body of the carbureter is a member, which may in a sense be regarded as a baffle, comprising a downwardly extending circular portion 36 120 which is situated at the central top portion of the section 1, surrounding an intermediate reduced portion of the member 20, a horizontally extending portion 37, a downwardly extending annular portion 38, and 125 an inwardly and downwardly inclined extending portion 39, all of said parts being integrally connected. The circular opening formed at the center of the downwardly and inwardly inclined portion 39 receives 130

the lower edge of the rotatable valve 31 and assists in holding the same in proper position.

It will be observed that the space between 5 the downwardly inclined portion 39 and the inner upper surface of the bottom wall of the section 1 is wedge shaped in cross section.

A second member, which also in a sense 10 may be regarded as a baffle, is also provided, said member being situated interiorly of the member comprising the angularly related parts 36, 37, 38 and 39. The said second member comprises an inner annular 15 portion 41 which surrounds and engages the corresponding annular portion 36, a horizontally extending annular portion 42, a depending annular portion 43, and a horizontal angular portion 44, said portions being 20 integrally connected with each other. The lower end of the part or portion 41 projects a considerable distance below the lower edge of the annular part 36. The annular portion 44 is provided with an opening through 25 which the valve 31 extends, the edges of said opening contacting with the portion 35 of the said valve intermediate the openings 32 and 33. The annular depending portion 41 is provided with a series of openings 45 30 as best shown in Fig. 1 of the drawings.

Situated within and extending transversely of the chamber formed by the parts 41, 42, 43 and 44 is an annular truncated cone-shaped member 46 which constitutes a 35 baffle plate to direct the course of the air which enters therein through the openings 45. Such air passes around the outer edge of the said baffle plate and thence forwardly underneath the same and thence 40 through the openings 32 into the annular space immediately above the annular member 22. From the latter space the air passes through the openings 26 into the annular chamber between the depending wall 24 and 45 the periphery of the member 21. Air also enters the annular space within the depending wall 24 from the space outside of the member 36, 37, 38, 39. The air is adapted to pass from the said annular space through 50 the openings 25 and 30 and through the openings 33 into the mixing chamber, between the said members formed of the parts 36, 37, etc. and 41, 42, etc. The passage of air through the openings 30 acts upon the oil which has issued from the nozzles 29 55 to atomize and vaporize the same. A spray is produced which mixes and intermingles with the air which passes through the openings 25 on opposite sides of the openings 30. 60 It will be observed that the portion of the mixing chamber or passage-way between the parts 39 and 44 is wedge-shaped in cross section and tapers from toward the center outwardly, but widens or flares in a direction 65 at right angles to the tapering direc-

tion. The extent of the taper is such that the capacity of the chamber at all transverse points is the same. The result is that a more efficient and complete intermingling and vaporization is effected than if the mixing 70 chamber or passage-way were of equal transverse thickness or width throughout. The vaporous fuel passes from the wedge-shaped portion of the chamber upwardly into the annular space between the parts 38 and 43 75 and thence into the transversely arranged relatively wide space between the parts 37 and 42, and thence through the opening in the top part 37 into the outlet passage 5 whence it travels to the engine, due to the 80 suction of the latter in known manner. The capacity of the annular space between the parts 38 and 43 is equal to the capacity of the portion of the mixing chamber space between the parts 39 and 44. 85

The passage of the air and liquid fuel through the openings in the depending wall 24 is controlled by the annular valve 31 which is secured to and moves with the member 20. The member 20 is operated simultaneously with and automatically as the butterfly valve 6 is operated, as heretofore stated. In order to operate the valve 6 the rod 51 is rotated by means of a throttle lever (not shown). The valve 6 is supported by the 90 rod 51. Depending from the said rod 51 is an arm 53 connected at its lower end with a link 50 which in turn is connected to an arm 54 having connection with a sleeve 55 which sleeve has a splined connection with the upper end portion of the spindle or member 20. It will be seen, therefore, that upon the turning of the rod 51 in a direction to close the valve 6 the arm 54 is turned toward the right, having reference to Fig. 4 100 105 of the drawings, with the result that the member 20 is turned to the left, that is in the direction opposite that in which the hands of a watch rotate. The relation of the annular valve 31 should be such that 110 as the valve 6 is closed the openings 25 and 30 in the depending wall 24 are successively closed, until all except one opening 30 and the two openings 25 on opposite sides thereof are closed. It follows that when the valve 115 is turned in the opposite direction to open the same the said holes are successively opened until all of them are opened when the valve 6 has been completely opened and when it is desirable that a full supply of the 120 explosive vapor shall be furnished to the combustion chamber of the engine.

It will be understood that in the operation of the device the liquid fuel is drawn into the carburetor through the conduit or 125 passage-way 8 as the result of and during the return or suction stroke of the engine piston. This is due to the creation of a vacuum or a partial vacuum in the carburetor chamber.

It should be noted that the parts 36, 37, etc. and 41, 42 etc. are stationary being supported in any suitable manner within the chamber of the body section 1.

- 5 In view of the fact that the air which is drawn through the inlet port 3 in the carbureter is heated the chambers outside of the member 36, 37, 38, 39 and with the member 41, 42, 43, 44 may be regarded and 10 termed as thermal chambers, since they contain heated air, the heat of which is transmitted by conduction to the mixed air and fuel within the fuel mixing chamber. It will be seen that the construction as described 15 provides for and includes a mixing chamber of such shape and arrangement that the atomized liquid fuel is thoroughly mixed with the air and is completely vaporized to produce an explosive vapor of a character 20 such that all of it is utilized in the engine so that there is a minimum loss of power and efficiency.

I have also shown means for introducing into the outlet passage or chamber 5 of the carbureter either an inflammable gas or high test inflammable liquid fuel, used in case of an emergency when the carbureter is not operating satisfactorily, as when it is cold and it is desired to start the engine, or 25 water which may be introduced and which acts as an aid to the low test fluid fuel. The said device comprises a three-way valve cock 61 which is connected by means of a tubular member 62 to the section 2 which tubular member 30 extends into the interior thereof terminating in the outlet passage 5. The inner end of the said tube is flattened out and corrugated as indicated at 63 in said Fig. 7, such corrugations dividing the exit 35 into a plurality of flaring perforated passage-ways 63'.

60 and 60' designate intake plugs having connection by means of the three-way cock and the passage-way through members 62 45 and 63 into the outlet chamber 5. The negative pressure in said chamber 5 is regulated by the throttle valve 6 during the operation of the carbureter. The intake plug 60 is adapted to be connected with an inflammable 50 gas supply tank through an adjustable, constant, pressure reducing valve of known type (not shown) while the intake plug 60' is adapted to be connected with a water supply tank through a float chamber or other 55 constant level device (not shown) from which the water is drawn which is introduced into the outlet passage 5. The supply of either liquid fuel or water is influenced by the throttle, opening and closing 60 thereof respectively increasing and decreasing the amount used.

In the modified form of construction, shown in Figs. 8 to 11, embodying my invention, the sections 1 and 2 are connected 65 together in any suitable manner and the air

is supplied through the inlet opening 3. The opening into an auxiliary air chamber is controlled by means of a valve 4 supported upon the rod 4'. By adjusting the nut at the outer end of said rod 4' the tension of the spring 4' is varied so as to vary the force necessary to depress the valve 4. The upper end of the central member or spindle 4' is reduced as indicated at 3' and is supported in a blind hole or socket in the upper wall 70 of the section 2. The lower end portion of the member 4' is reduced as indicated at 5' so that an annular chamber surrounding the said reduced portion may be formed by the annular valve 15'. The lower or bottom 75 wall of the section 1 of the carbureter is provided with an extension having a passage-way 11' therethrough, said passage-way connecting a fuel supply tank (not shown) through a float chamber (not shown) with 80 the passage-way 11" for the supplying of liquid fuel to the carbureter. The lower end of the said passage-way 11' terminates in a cock 10 for the same purpose as described in connection with the cock 10 85 shown in Fig. 1. The inner side of the bottom wall of section 1 is provided with a recess 8' in which the passage-way 11' terminates. A cap 9' is seated within the said recess 90 said cap being provided with a boss upon its lower side which rests upon the central portion of the said recess. The outer edge portions of the said cap 9' are spaced from the bottom of the said recess so that an annular chamber is formed between the outer edges 95 of said cap and the bottom of said recess. The cap is secured in position by means of screw 10'. The upper side of the cap is provided with a boss or projection which extends into a recess formed in the lower 100 end of the member 4'. By reason of the formation of the reduced portion 5' upon the member 4' a flange 6' is formed at the lower end thereof which flange is seated upon the cap 9', its edge being in alinement 105 with the edge of the said cap. The cap 9' is provided in its lower side and at its center with a shallow recess from which extend a plurality, three being shown, of radiating passage-ways 9" best shown in Fig. 10 of the 110 drawings. The outer ends of these passage-ways communicate with the annular chamber surrounding the boss upon the lower side of the cap 9'. A plurality of radiating passage-ways 12' are also formed in the bottom 115 wall of section 1 of the carbureter chamber, said radiating passage-ways being best shown in Fig. 10 of the drawings. The outer ends of these passage-ways communicate with the upright tubular members 13' 120 constituting liquid fuel discharge nozzles the upper ends of which terminate in the mixing chamber of the carbureter. Said ends are in alinement substantially with the holes 20" formed in the outer ring 125 130 of an

annular member which consists of three rings 52, 52' and 52'' secured together. The openings 20'' are considerably wider in a direction parallel with the rings than the holes 20' which are formed in the inner annular rings 52'' of the said annular member. The openings 20', however, are of greater length vertically considered than the openings 20'' so that the capacity of the two openings are respectively substantially the same. The areas of the respective holes 20'' in the ring 52' should be equal to or greater than that of the respective holes 20' and 20'' and their width or height transversely of the ring 52' should be equal to the length of the holes 20' while in a direction parallel with the said ring they should be of a width equal to or greater than the holes 20''. The annular valve 15' is supported upon the rotatable member 4', said rotatable member being rotated by means of the sleeve 55 in the same manner as described in connection with the construction shown in Figs. 1 to 7 inclusive.

25 The lower edge of the annular valve 15' is seated within an annular groove formed in the bottom of the recess 8' as shown in Figs. 8 and 10 of the drawing. When the said valve is in closed position, as shown in Fig. 9, it closes all except one of the radial passage-ways 12'. When the said valve is turned in a direction to open the same the passage-ways are successively opened by reason of the presence of the openings 16'.

30 The member consisting of the parts 36, 37, 38, and 39 is substantially the same in construction as the member which includes the same parts in the construction shown in Figs. 1 to 7 inclusive. The member comprising the parts 41, 42, 43, and 44 is substantially the same in construction as the member including the correspondingly numbered parts shown in Fig. 1 of the drawings, the only difference being that in the modified 45 construction the said member is provided with an auxiliary air inlet opening at 41' which is closed by means of the valve 4.

The inner edge of the parts 39 and 44 terminate in contact with and support the 50 annular member comprising the rings 52, 52' and 52''. The tubular passage-ways 13' project through openings formed at intervals in the edge of the said part 39.

Extending diagonally of the chamber 55 within the parts 41, 42, etc., is an annular plate 42' which divides the said chamber into two annular chambers as is apparent from Fig. 8 of the drawings. The said inclined annular member 42' is provided with 60 a plurality of openings 43' which are adapted to be controlled by means of an annular rotatable valve 44' said valve being rotated by means of an arm 4'' having connection with the rotatable member 4'. The openings in the valve member 44' are of different

and graduating lengths similar to the openings 18' in the valve 15' so that the openings 43' in the annular member 42' are opened and closed successively when the valve 44' is rotated.

Also situated within the chamber formed by the parts 41, 42, etc., and below the annular plate 42' is a truncated cone-shaped baffle plate 46 the outer edge of which is situated adjacent to the upright part 43. 70 The portion of the heated air which passes from the inlet 3 into the annular space inside of the part 36 passes through openings 45 into the space below the inclined annular plate 42' and thence around the outer edge 75 of the baffle plate 46 underneath the same and through openings 19' into the annular chamber surrounding the reduced portion 5' of the member 4'. When the annular valve 44' is rotated (which occurs when the member 4' with the member 4'' is rotated to move the valve 15' to open it) so as to open the openings 43' and the vacuum created in the chamber of the carburetor by the suction of the engine is such that the excess of 80 pressure of the atmosphere upon the outside of the valve 4 over the pressure of the air upon the inside, said valve 4 is opened to permit air to enter the auxiliary air chamber above the inclined annular plate 42'. It 85 then passes through the openings 43' and through tubular connections 47' to the portion of the mixing chamber intermediate the parts 39 and 44.

The heated air which enters the inlet 3 100 and travels downwardly upon the outside of the part 38 passes forwardly underneath the part 39 around the tubular members 13' and through the openings 17' into the annular chamber surrounding the reduced portion 5' of the member 4'. This air, as well as that which has entered through the openings 19' before described is permitted to pass, when the valve 15' is open, through the graduated openings 18' through the 105 openings 20', 20'' and 20''. As the air issues from the openings 20' some of it strikes against the edge of the openings at the upper ends of the tubular members 13' and acts upon any liquid fuel which may 110 be present upon the said edges to vaporize the same.

The liquid fuel is discharged from the upper ends of the tubular members 13', is absorbed and atomized by the air as it 115 escapes from the opening or openings 20''.

Under certain conditions of operation, as when the engine is not working at its full capacity, the partial vacuum created or formed in the chamber underneath the valve 4 by the return stroke or strokes of the piston of the engine cylinders is not sufficient to allow the excess of pressure of the atmosphere upon the outside of the valve to overcome the resistance of the spring 4' and 120

cause downward movement of said valve to open it. Under certain other conditions of operation, however, as when the engine is operating at its highest capacity and when 5 greater quantities of liquid fuel are introduced into the vaporizing chamber when consequently a greater quantity of air is necessary to furnish the proper proportion of air to the liquid fuel supplied to the mixing 10 chamber, the said valve is opened so that an auxiliary supply of air is produced. When the valve 4, in the form of construction shown in Fig. 1, does not open the air supply for the carbureter enters through the 15 holes 4^a and 4^b and, in the construction shown in Fig. 8 of the drawings, the air passes to the mixing chamber through the holes 45 and through the annular chamber between the parts 38, 39 and the wall of the 20 section 1 of the carbureter body.

It not only may but probably would be the case that the valve 4 would remain closed and would be opened under conditions other than those presupposed above, 25 such conditions as presupposed being merely taken by way of example.

The construction is such, as already indicated, that the capacity of the mixing chamber, not only that portion of it which occupies 30 the space between the parts 39 and 44 but also that portion thereof which occupies the space between the parts 39 and 43, is the same capacity at all points.

By my invention the liquid fuel and the 35 air are so thoroughly intermixed and intermingled that the said fuel is completely vaporized so that the mixture acts with a maximum of efficiency without any loss of power which might be due to improper vaporization.

It may be noted that the valve 15' is shown in Fig. 9 in the position it occupies when the butterfly valve 6 is in closed position. As the throttle lever (not shown) is 45 operated to open the valve 6, the valve 15' is turned to the right so that the openings 20' are successively opened as described. The capacity of the carbureter is thus increased by using more of the atomizing chamber and 50 diminished by using less of said chamber.

I claim:—

1. A carbureter comprising a casing, having an air inlet, a combustible mixture outlet, and a fuel supply, a plurality of baffles 55 in the casing, a central spindle rotatably

mounted in the casing, means for rotating the spindle, and means carried by said spindle, and co-acting with means carried by the baffles to regulate the flow of air and fuel through the carbureter.

60

2. A carbureter comprising a casing having an air inlet, a combustible mixture outlet, and a fuel supply, a central rotatable spindle, stationary baffles surrounding the spindle, a perforated member carried by the 65 spindle, a perforated member carried by the baffles, and means to rotate the spindle to position the first mentioned perforated member with respect to the last mentioned perforated member to regulate the flow of air 70 and fuel through the carbureter.

3. A carbureter comprising a plurality of atomizers, a mixing chamber to receive the mixture of fuel and air from said atomizers, the walls of said chamber extending radially 75 and converging toward each other so that the capacity of said chamber remains constant, a valve for controlling the said atomizers, and means for moving the said valve to open and close the said atomizers successively.

4. In a carbureter, the combination of a mixing chamber comprising angular and annular members arranged concentrically with respect to each other, the inner lower edges 85 of the said members being spaced apart, an annular member situated in the openings through the lower parts of said members said annular member having openings therethrough, an annular valve having openings 90 adapted to register with the said annular member, means for causing movement of the said annular valve for opening and closing the openings in the said annular member, passage-ways for discharging liquid fuel 95 into the said mixing chamber at points adjacent to and in alignment with the openings through the said annular member, and means for discharging air through the said openings in the said annular member to vaporize and atomize the fuel discharged from the said openings, substantially as described.

In testimony that I claim the foregoing as my invention, I have hereunto signed my name this 8th day of April, A. D. 1915.

JAMES C. HENRY.

In the presence of—

J. R. WARE,

A. T. WOODWARD.
